(57) **CLAIM**

The ornamental design for a fishing hook protector, as
shown and described.

DESCRIPTION

FIG. 1 is a top perspective view of a fishing hook protector
mounted on a fishing hook, the broken line illustration of the
fishing hook is for illustrative purposes only and forms no
part of the claimed design;

FIG. 2 is a bottom perspective view of the fishing hook
protector;

FIG. 3 is a front elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a top perspective view, with the broken lines being
for illustrative purposes only and forming no part of the
claimed design; and,

FIG. 9 is a bottom perspective view thereof.
